UNITED STATES PATENT OFFICE.

ROY C. ARNOLD, OF FRESNO, CALIFORNIA.

GAME BOARD.

Application filed July 31, 1922. Serial No. 578,633.

To all whom it may concern:

Be it known that I, Roy C. ARNOLD, a citizen of the United States, and resident of Fresno, in the county of Fresno, State of California, have invented certain new and useful Improvements in Game Boards, of which the following is a specification.

My invention relates primarily to a game board of a substantially rectangular shape, 10 although any other desired shape may be used, provided with pockets, playing discs and a shooter, the object being to shoot the discs with the shooter into the designated pockets in the board. A number of players 15 usually take part in the game, the player succeeding in pocketing the largest number of discs winning the game.

Other objects and advantages will appear hereinafter and, while I have shown and 20 will describe the preferred form of my invention, I wish it to be distinctly understood that I do no limit myself to such preferred form but that various changes and adaptations may be made therein without departing 25 from the spirit of my invention.

In the drawings accompanying and forming a part hereof:

Fig. 1 is a top plan of my board in position for use.

30 Fig. 2 is a right hand elevation of Fig. 1.

Fig. 3 is a section on the line 3—3 of Fig. 1.

Fig. 4 is an enlarged section on the line 4—4 of Fig. 1.

35 Figs. 5 and 6 are enlarged sectional details of the turn table upon which my board is mounted.

Fig. 7 is a plan view of one form of my shooter in its operative position.

40 Fig. 8 is a plan view of my shooter in its discharged position.

Fig. 9 is a perspective view of one of the discs used with my board.

Referring to the drawings, my device comprises a shallow, substantially rectangular, 45 tray composed of a bottom 10 surrounded at its edges by the upstanding rim 11, the inner top edge of rim 11 being bevelled as at 12. Provided in each of the corners are 50 pockets 13, the walls of which are lined with a shock absorbing material, such as felt, or the like, 14, and the bottoms of which are closed by fabric closures 15. Projecting downwardly from the under side of bottom 10, centrally thereof, is a hub or boss 16, centrally of which is revolubly mounted the

turn table. This turn table is composed of arms 17 and 18 pivotally connected together centrally of their length to extend at right angles to each other. As will be noted in 60 Figs. 5 and 6, members 17 and 18 are connected loosely together at their centers, the purpose of which will be hereafter explained. Revolubly mounted on the ends of members 17 and 18 are rollers 19 which 65 are of a diameter and so positioned as to bear against the under side of bottom 10 and serve to support the same.

In Figs. 7 and 8 I have shown one form 70 of shooter adapted for use with my device. This form comprises a hollow cylindrical handle 20 closed at one end. Sidably mounted in handle 20 is the sliding member 21, the free end of which terminates in a tip 22 of rubber or any other suitable material. Provided in handle 20, intermediate its ends, is a slot 23 the lower end of which terminates in an offset portion 24, and mounted in member 21, near the inner end thereof, is a retaining pin 25 the free end of which projects 75 into and through slot 23. Mounted within handle 20, between the closed end thereof and the inner end of member 21, is a coil spring 26 by means of which member 21 is caused to move outwardly. Pin 25 is adapted to be mounted in offset 24 to hold member 21 in its retracted or operative position.

In Fig. 9 I have shown one of the discs 80 used with my game board which is normally formed of hard wood or other semi-resilient material.

In the use of my game board a shooter disc is used with the shooter, the object being to strike the shooter disc with the shooter and cause the shooter disc to strike one of the 85 playing discs and project the same into one of the pockets 13, the turn table being provided so that the players may rotate the table to bring the shooter disc into proper position to play on, thus obviating the necessity of walking around the board.

Having described my invention what I claim is:

1. A game board comprising a substantially rectangular base; an upstanding rim 105 surrounding said base; an inwardly opening recess in each of the corners of said base the recesses in the opposed corners opening towards each other; an opening in said base immediately below each of said recesses; a 110 flexible closure for the under sides of each of said openings; a disc secured to the un-

der side of said base centrally thereof having a central opening therein; in combination with a turn table upon which said base is mounted comprising a pair of arms rigidly connected together centrally of their length to extend at right angles to each other; a pivot extending upwardly centrally of said arms adapted for engagement with the opening in said disc; a roller revolvably mounted on each end of each of said arms at right angles thereto adapted to bear against the under side of said base.

2. In a game board the combination of a substantially rectangular base; an upstanding rim surrounding said base; an inwardly opening recess in each of the corners of said base, opening radially; openings in said base immediately below each of said recesses and being of a configuration to form a continuation thereof; a fabric closure for the lower

ends of said openings; a shock-absorbing lining for the side walls of said recesses; a bearing extending downwardly from said base centrally thereof; in combination with a turn table upon which said base is revolvably mounted comprising a pair of arms rigidly connected together centrally of their length to extend at right angles to each other, adapted to rest upon a stationary support; a pivot extending upwardly from said arms centrally thereof adapted to be revolvably mounted in said bearing; and a roller revolvably mounted on each end of said arms at right angles thereto, adapted to bear against the under side of said base.

In witness that I claim the foregoing I have hereunto set my hand this 21st day of July, 1922.

ROY C. ARNOLD.
